UNITED STATES PATENT OFFICE.

FRANCIS H. RICHARDS, OF HARTFORD, CONNECTICUT.

PROCESS OF MAKING PLAYING-BALLS.

No. 850,253.

Specification of Letters Patent.

Patented April 16, 1907.

Application filed June 2, 1902. Serial No. 109,905.

To all whom it may concern:

Be it known that I, FRANCIS H. RICHARDS, a citizen of the United States, residing at Hartford, in the county of Hartford and State of Connecticut, have invented certain new and useful Improvements in Processes of Making Playing-Balls, of which the following is a specification.

This invention relates to a process of manufacturing playing-balls, more especially to the form employed in the game of golf; and the invention consists substantially in the improvements hereinafter particularly described.

15 In the accompanying drawings, Figure 1 is a sectional view representing an unexpanded center piece or filler, of soft rubber or similar material, employed in the manufacture of my improved ball. Fig. 2 is a sectional view 20 representing the center piece or filler of the ball with a layer or envelop of gutta-percha applied thereto. Fig. 3 is a similar view representing a fabric-lined layer or envelop of celluloid applied to the structure shown in Fig. 2. Figs. 4 and 5 are sectional views 25 illustrating means employed in intermediate stages of manufacture of the ball. Fig. 6 is an enlarged sectional view of a fragment of my improved ball, illustrating the construction more clearly; and Fig. 7 is an enlarged 30 sectional view of the mold employed in the manufacture of my improved ball, showing in part section a completed ball located in the mold.

35 In proceeding to manufacture a playing-ball in accordance with my present improved process I first provide a spherical center piece or filler, of soft rubber or similar material, and form therein a perforation 2, in the 40 wall of which is a vent 2', the numeral 3 designating the outer surface of the said center piece or filler and the numeral 4 the inner surface thereof. Upon this center piece or filler I apply an envelop 5, of gutta-percha or 45 analogous material, and to the latter I apply a fabric-lined envelop 6, preferably of celluloid or its equivalent. The envelop 6 may be applied while the celluloid is in a plastic condition and then allowed to harden to an 50 extent to permit handling with safety. If desired, the fabric and celluloid may be separately applied one after the other, and each of the several envelops may also be otherwise applied than herein described and be within 55 the scope of my invention, it being desirable that all the envelops be loosely arranged.

The ball thus assembled I inclose in a mold *a*, consisting of two parts *a'* and *a''*, having a pair of hemispherical depressions *b'*, which together form a spherical cavity or chamber *b*. The mold is also provided above the said spherical cavity or chamber *b* with a cylindrical bore *c*, formed by opposite recesses *c'* in the parts of the mold, and in said bore works a piston *e*. In the hole *d*, which is formed by recesses *d'* in the parts of the mold, is inserted a funnel *f*, having a flange *f'*. The part *a''* of the mold is provided with a transverse perforation *g*, the wall of which is screw-threaded at *h* to receive a threaded plug *j*, and the two parts of the mold may be provided with dowels *k*.

When the ball is placed in the mold, the lower part of the funnel passes through the perforation *g* and communicates with the cavity 4 of the spherical center piece or filler 1. In the bore *c* of the mold is placed a quantity of gutta-percha *7'*, which is rendered fluent by heat, and said fluent material is forced into the hollow spherical center piece or filler by the piston *e*, as indicated at Fig. 4, the displaced air escaping through the vents *2'* and *g*, whereupon the plug *j* may be inserted, as at Fig. 5, and the piston forced farther down to cause the gutta-percha to expand the rubber center piece or filler and its several envelops to the limits permitted by the sides of the mold-chamber. A vent *8* may be provided for the escape of air from the chamber. In this way the spherical rubber center piece or filler is materially increased in diameter and put under tension, while the gutta-percha and celluloid of the envelops being rendered plastic by heat are caused to conform to the shape of the mold-chamber, the surfaces of the walls of which are provided with pits, as herein shown, so as to form brambles upon the outer surface of the completed ball. The pressure is maintained upon the piston *e* until the entire ball structure cools and hardens, and on the completion of the ball the perforation *2'* may be filled by a plug *9*.

Variations may be resorted to within the scope of my improvements, it being apparent, for instance, that the fabric lining *6'* between the outer envelop of celluloid and the inner envelop of gutta-percha may be omitted or other material substituted therefor.

Having described my invention, I claim—

1. A process of making a playing-ball consisting in applying to a hollow spherical elas-

tic center piece an envelop of gutta-percha, then applying a fabric-lined envelop, and finally placing the structure under distention by injecting into the center piece a mass of material rendered fluent by heat and adapted to harden on cooling.

2. A process of making a playing-ball consisting in applying to a spherical hollow center piece a loose envelop of gutta-percha, then applying a loose fabric-lined envelop, and finally placing the structure under distention by injecting into the center piece a mass rendered fluent by heat and adapted to harden on cooling.

15 3. A process of making a playing-ball consisting in applying to a hollow spherical elastic center piece an envelop of gutta-percha while hot, then applying a fabric-lined envelop also under heat, and finally placing the structure under distention by injecting thereinto a mass rendered fluent by heat and adapted to harden on cooling.

20 4. A process of making a playing-ball consisting in applying to a hollow spherical elastic center piece an envelop of gutta-percha, then applying a fabric-lined envelop, and finally placing the structure under distention by injecting into the center piece a mass of gutta-percha rendered fluent by heat and allowing the mass to cool.

25 5. A process of making a playing-ball consisting in applying to a hollow spherical elastic center piece a loose envelop of gutta-percha, then applying a loose envelop of fabric-lined material, and finally placing the structure under distention by injecting fluent gutta-percha into the center piece and allowing the mass to cool.

30 6. A process of making a playing-ball con-

sisting in applying to a hollow spherical elastic center piece an envelop of gutta-percha, then applying an envelop of fabric-lined material, and finally placing the structure under distention by injecting thereinto a mass rendered fluent by heat and adapted to harden on cooling, and simultaneously imparting to the structure a spherical form externally.

35 7. A process of making a playing-ball consisting in applying to a hollow spherical elastic center piece a loose envelop of gutta-percha, then applying a loose envelop of fabric-lined material, and finally placing the structure under distention by injecting thereinto a mass rendered fluent by heat and adapted to harden on cooling, and simultaneously imparting to the structure a spherical form externally.

40 8. A process of making a playing-ball consisting in applying to a hollow spherical elastic center piece an envelop of gutta-percha, then applying an envelop of fabric-lined material, and finally placing the structure under distention by injecting fluent gutta-percha into the center piece, and simultaneously imparting to the structure a spherical form externally.

45 9. A process of making a playing-ball consisting in applying to a hollow spherical elastic center piece a loose envelop of gutta-percha, then applying a loose envelop of fabric-lined material, and finally injecting fluent gutta-percha into the center piece and simultaneously imparting to the structure a spherical form externally.
